UNITED STATES PATENT OFFICE.

EMMA M. REQUA, OF NEW YORK, N. Y.

DESIGN FOR A BADGE.

SPECIFICATION forming part of Design No. 19,426, dated November 12, 1889.

Application filed August 30, 1889. Serial No. 322,462. Term of patent 3½ years.

To all whom it may concern:

Be it known that I, EMMA M. REQUA, a citizen of the United States, residing in the city, county, and State of New York, have 5 invented and produced a new and original Design for a Badge, of which the following is a specification, reference being had to the accompanying drawing, forming a part hereof. The design consists of the representation 10 of a ship constituting a pin, from which is suspended a disk or representation of the Western Hemisphere. The accompanying drawing shows an old-fashioned ship A of the style of 1492, which

constitutes the pin, from which a ribbon or 15 other connection C depends. A pendant D, suspended by the connection C, has thereon a representation of the three Americas.

Having thus fully described my new and original design, what I claim is—

20 The design for a badge, substantially as herein shown and described.

In testimony whereof I have hereunto subscribed my name.

EMMA M. REQUA.
